DRY PLACER MACHINE

Otto Nolte, Twin Bridges, Mont.

Application February 29, 1936, Serial No. 66,489

7 Claims. (Cl. 209—44)

The invention relates to a dry placer machine and more especially to an automatic dry concentrator.

The primary object of the invention is the provision of a machine of this character, wherein through the use of riffles of a particular formation the fine precious metal can be conveniently separated from the coarser particles of lower specific gravity so that this fine material can have discharge at a point away from the heavy material and at the bottom of the machine, the machine being of the vibrating type and is of novel construction and will positively screen the finer material from the coarse and separate the gold and concentrates from the sand in a single operation.

Another object of the invention is the provision of a machine of this character, wherein damp or dry material can be conveniently handled for separating the heavier material from the light, the riffles employed in the machine being susceptible of raising movement so as to release the material therefrom for its deposit in a suitable receptacle without necessitating the stopping of the machine in its operation.

A further object of the invention is the provision of a machine of this character, which is comparatively simple in its construction, thoroughly reliable and efficient in its operation, strong, durable, and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a side elevation partly in section of a machine constructed in accordance with the invention.

Figure 2 is a top plan view thereof.

Figure 3 is a fragmentary end elevation looking toward the discharge end of the machine.

Figure 4 is a side elevation of the machine.

Figure 5 is a fragmentary vertical transverse sectional view showing in detail the bearings for a movable part of the machine.

Figure 6 is a fragmentary enlarged elevation of the eccentric rod and adjuncts.

Similar reference characters indicate corresponding parts throughout the several views in the drawings.

Referring to the drawings in detail, the machine comprises a main frame 10 including verti-

cal legs or uprights 11 and braces 12, these being made secure in any suitable manner to give rigidity and strength to the main frame. Upon the main frame 10 is supported an inclined vibrating box 13 having fixed thereto upstanding leaf-like springs 14, these being bolted or suitably secured to the main frame 10 and are also engaged between cleats 15 as carried by the sides 16 of the box 13 and thus the latter is held for vibration.

At one end of the box 13, that is to say the high end thereof, is a feed chute or hopper 17 which leads to a shuffle plate or feed plate 18 located within the box and having an incline corresponding to the incline of said box and above such plate is a screen 19 which is substantially in the same plane with a top or coarse material discharge floor 20, the bottom 21 of said box being of a construction to provide a lower or concentrates floor having air deflectors 22. Rearwardly with respect to the deflectors 22 is a throat 23 having loose connection with the outlet nipple 24 of a blower casing 25 in which is journaled a bladed blower wheel 26, its axle 27 being journaled in bearings 28 of the ball type and each bearing is built with a lubricating vent or passage 29 and such bearings are fitted with the main frame 10.

On the axle 27 is a belt wheel 30 having trained thereover the belt 31 which is also trained over a belt wheel 32 driven from a motor unit 33 through the belt and pulley connections 34. It is preferable to have the motor 33, which is of the internal combustion type, supported by a base 35 fitted with the uprights 11 of the main frame 10.

The belt wheel 32 is carried by a shaft 36 suitably journaled in bearings 37 on the main frame 10 and this shaft carries an eccentric 38 fitting the strap end 39 of an eccentrically operated throw rod 40 which is also pivoted at 41 to the under side of the box 13 toward the lower end thereof and in this manner the box is vibrated through the influence of the stroke of the rod 40 as actuated by the eccentric 38.

Between the floors 20 and 21 and extending from the plate 18 to the discharge end of the box 13 is a fine or concentrate screen 42, it being disposed at an incline greater than the incline of the box. Cooperating with the screen 42 is a riffle assembly in the form of a ladder 43 and the rungs of which constitute the stream line riffles 44 which in pairs have straight walls 45 and the curved portions 46, respectively, the straight walls 45 of each pair being in confronting rela-

tion to each other and spaced apart as is clearly shown in Figure 1 of the drawings. These riffles at the bottoms thereof carry felt strips 47 for contact with the screen 42 to eliminate the es-
 5 caping of material between the riffles and said screen at the points of contact of the felt strips 47 with the latter. The ladder 43 is hinged by pivots 48 to the sides of the box 13 for vertical swinging movement and the handle ends 49 of
 10 this ladder extend beyond the discharge end of the box 13 for manual lifting of the said ladder. The riffles 44 of the ladder 43 are held in close relation to the screen 42, that is to say the ladder 43 is placed against said screen under the influence of a spring 50 having connection at 51 with the box and at 52 with the handle 49. Thus it will be seen that the ladder 43 can be raised to free trapped coarse material for the discharge thereof from the screen 42.

30 The floor 21 next to the discharge end of the box 13 has a concentrates slot 53 opening into a delivery spout 54 for communication with a catch drum, pan or other container 55.

The blower directs a blast of air through the throat 23 and through the screen 42 and in conjunction therewith the vibration of the box 13 enables a quick separation of the finer particles from the coarser particles of lower specific gravity of material and these finer particles are dis-
 25 charged through the spout 54 while the larger particles are precipitated over the riffles 44 and delivered from the discharge end of the box 13 so that finer material will be successfully separated from the coarser particles in the working
 30 charged through the spout 54 while the larger particles are precipitated over the riffles 44 and delivered from the discharge end of the box 13 so that finer material will be successfully separated from the coarser particles in the working
 35 of the machine. The coarser particles are maintained above the screen 42 as the finer material or particles pass through the said screen 42 for deposit on the floor 21 and under the air blast both the coarser particles of lower specific gravity and finer particles of higher specific gravity are precipitated toward the discharge end of the machine, the coarser particles being delivered therefrom at a point different from the delivery of the finer materials or particles through the
 40 45 spout 54.

It is preferable to feed the raw material from the chute or hopper 17 onto the first screen 19, this being the coarse screen in the equipment of the machine, the screen 42 being the fine screen.

50 The box 13 at the discharge end thereof is open above the screen 42 and closed below it so that the concentrates as carried upon the floor 21 can only be delivered from the box 13 through the slot 53 into the spout 54.

55 What is claimed is:

1. A machine of the character described comprising a stand, upright leaf spring members carried thereby, an inclined vibrating box carried by said springs and having a bottom forming a concentrates floor, a feed plate, fine and coarse screens within said box and related with the feed plate, a top coarse discharge board within said box, a throat formed with the bottom of said box, a blower having loose connection with said throat, means for vibrating the box, and a rifle ladder swingingly mounted within the box and resting upon the fine screen.

2. A machine of the character described comprising a stand, upright leaf spring members carried thereby, an inclined vibrating box carried by said springs and having a bottom forming a concentrates floor, a feed plate, fine and coarse screens within said box and related with the feed plate, a top coarse discharge board within
 70 said box, a throat formed with the bottom of said
 75

box, a blower having loose connection with said throat, means for vibrating the box, a rifle ladder swingingly mounted within the box and resting upon the fine screen, and a spout communicating with the box through its bottom at the lower end of the latter.

3. A machine of the character described comprising a stand, upright leaf spring members carried thereby, an inclined vibrating box carried by said springs and having a bottom forming a concentrates floor, a feed plate, fine and coarse screens within said box and related with the feed plate, a top coarse discharge board within said box, a throat formed with the bottom of said box, a blower having loose connection with said throat, means for vibrating the box, a rifle ladder swingingly mounted within the box and resting upon the fine screen, a spout communicating with the box through its bottom at the lower end of the latter, and riffles in said ladder and having rounded sides and a straight wall, the straight walls of adjacent riffles being spaced and in confronting relation to each other.

4. A machine of the character described comprising a stand, upright leaf spring members carried thereby, an inclined vibrating box carried by said springs and having a bottom forming a concentrates floor, a feed plate, fine and coarse screens within said box and related with the feed plate, a top coarse discharge board within said box, a throat formed with the bottom of said box, a blower having loose connection with said throat, means for vibrating the box, a rifle ladder swingingly mounted within the box and resting upon the fine screen, a spout communicating with the box through its bottom at the lower end of the latter, riffles in said ladder and having rounded sides and a straight wall, the straight walls of adjacent riffles being spaced and in confronting relation to each other, and air deflectors on the bottom of said box.

5. A machine of the character described comprising a stand, upright leaf spring members carried thereby, an inclined vibrating box carried by said springs and having a bottom forming a concentrates floor, a feed plate, fine and coarse screens within said box and related with the feed plate, a top coarse discharge board within said box, a throat formed with the bottom of said box, a blower having loose connection with said throat, means for vibrating the box, a rifle ladder swingingly mounted within the box and resting upon the fine screen, a spout communicating with the box through its bottom at the lower end of the latter, riffles in said ladder and having rounded sides and a straight wall, the straight walls of adjacent riffles being spaced and in confronting relation to each other, air deflectors on the bottom of said box, and felt strips carried by the riffles and contacting with the fine screen.

6. A machine of the character described comprising a stand, upright leaf spring members carried thereby, an inclined vibrating box carried by said springs and having a bottom forming a concentrates floor, a feed plate, fine and coarse screens within said box and related with the feed plate, a top coarse discharge board within said box, a throat formed with the bottom of said box, a blower having loose connection with said throat, means for vibrating the box, a rifle ladder swingingly mounted within the box and resting upon the fine screen, a spout communicating with the box through its bottom at the lower end of the latter, riffles in said ladder and having rounded sides and a straight wall, the straight walls of

adjacent riffles being spaced and in confronting relation to each other, air deflectors on the bottom of said box, felt strips carried by the riffles and contacting with the fine screen, and means active upon the ladder to maintain the same in position for the contact of the felt strips with the said fine screen.

7. A machine of the character described comprising a stand, upright leaf spring members carried thereby, an inclined vibrating box carried by said springs and having a bottom forming a concentrates floor, a feed plate, fine and coarse screens within said box and related with the feed plate, a top coarse discharge board within said box, a throat formed with the bottom of said box, a blower having loose connection with said

throat, means for vibrating the box, a riffle ladder swingingly mounted within the box and resting upon the fine screen, a spout communicating with the box through its bottom at the lower end of the latter, riffles in said ladder and having rounded sides and a straight wall, the straight walls of adjacent riffles being spaced and in confronting relation to each other, air deflectors on the bottom of said box, felt strips carried by the riffles and contacting with the fine screen, means active upon the ladder to maintain the same in position for the contact of the felt strips with the said fine screen, and handle ends on said ladder and projected beyond the lowermost end of the box.
